UNITED STATES PATENT OFFICE.

JOHN G. WRIGHT AND HARRY F. BENNETT, OF CHICAGO, ILLINOIS; SAID BENNETT
ASSIGNOR TO SAID WRIGHT.

DOOR-STRIP.

1,396,085.

Specification of Letters Patent.

Patented Nov. 8, 1921.

Application filed January 20, 1921. Serial No. 438,616.

To all whom it may concern:

Be it known that we, JOHN G. WRIGHT and HARRY F. BENNETT, citizens of the United States, residing at Chicago, in the county of Cook and State of Illinois, have invented certain new and useful Improvements in Door-Strips, of which the following is a description.

Our invention relates to improvements in door strips and more particularly to a device for closing the open space between the bottom of the door and the floor or doorsill in order to keep out the elements such as wind, rain, snow, etc.

Another object of our invention is to provide a device as above described which shall be self-operating to close the opening whenever the door is closed and which requires no manual aid whatsoever.

With a device of our invention applied to a door, a room can be easily kept warm and clean, for the strip prevents any dust from blowing in and prevents the heat in the room from passing to the outdoors through said opening.

Another object of our invention is to provide a device as above described, which will be simple, durable, economical, compact, efficient, and satisfactory for use wherever found applicable.

Many other objects and advantages of the construction herein shown and described will be obvious to those skilled in the art from the disclosure herein given.

To this end our invention consists in the novel construction, arrangement and combination of parts herein shown and described and more particularly pointed out in the claim.

In the drawings, wherein like reference characters indicate like or corresponding parts;

Figure 1 represents our device as applied to a door, the door being shown in its closed position;

Fig. 2 is a view similar to that shown in Fig. 1, the door being open;

Fig. 3 is a vertical section partly in elevation;

Fig. 4 is a section on the line 4—4 of Fig. 3; and

Fig. 5 is a section similar to Fig. 4, showing the device when the door is open.

In the embodiment of our invention illustrated in the drawings, A represents a door 55 of any suitable construction adapted to swing within a frame having the usual vertical jamb B, the door being suitably supported by hinges C or any other suitable or equivalent structure.

The door strip is applied to the bottom of the door, preferably on the outer side, and comprises a pair of telescopic or nesting slide members 1 and 2, the member 1 made of a strip of metal preferably bent into a 65 U-shape, as shown in Figs. 4 and 5, and having parallel spaced legs 3 connected by a web, said member being secured to the door by screws or equivalent means 5 which extend through the legs 3.

The member 2 is also preferably of U-shaped cross-section and comprises spaced legs 6 connected by a web, said member 2 being of a length substantially equal to the width of the door. The member 2 is suspended within the slide member 1 by means of links 7 or equivalent means for the purpose, said links being pivoted at one end to the member 1 by pivot pins 8 and being pivoted at the other end to the member 2 80 by pivot pins 9, the upper web of said member 2 being slotted to receive the links 7, said slots being substantially of a length equal to the length of the links, whereby the member 2 may be swung upwardly and 85 longitudinally of the member 1, so that the web of the member 2 approaches the web of the member 1, as shown in Fig. 3.

When the member 2 has been moved longitudinally of its guide member 1, (to the left 90 as shown in Fig. 2) when the door is opened, one of its ends, as 10, will project beyond the edge of the door, so that when the door is being closed, the path of movement of the end 10 will be across the (left hand) vertical jamb B, so that the end 10 bearing against this jamb will cause the member 2 to be slid or swung (to the right) to its closed position. Inasmuch as this swinging movement will be in a circular arc about the 95 pivot pins 8, the member 2 will be forced downwardly as well as longitudinally into its lowermost position.

A strip of rubber, felt, fabric, or other suitable and yieldable material 14, is preferably positioned on the lower end of the 105

member 2 so that it will adjust itself to any irregularities in the surface of the floor or sill, and prevent the wearing of the floor due to its friction contact therewith.

5 In order that the slidable strip member 2 may be constantly urged into engagement against the door jamb B there is provided a spring 11, secured at one of its ends 12 to the member 1, and secured at its other end 13 to the member 2. As shown in Fig. 3, this spring will exert the pull on the member 2 when the door is opened, and will cause the member 2 to move upwardly and to the left and out of engagement with the floor or sill when the door is opened.

10 When the door is being closed the end 10 of the member 2 will be pushed longitudinally and downwardly of the guide member 1 on account of its bearing contact with the jamb B, so that the opening between the bottom of the door and the floor will be closed. If desired, a wearing plate 15 of 20 any suitable material may be secured to the vertical jamb near its bottom and against which the end 10 of the strip member will 25 bear.

Having thus described our invention it is obvious that various immaterial modifications may be made in the same without departing from the spirit of our invention; 30 hence we do not wish to be understood as limiting ourselves to the exact form, arrangement, construction and combination of parts herein shown and described or uses 35 mentioned.

What we claim as new and desire to secure by Letters Patent is:

The combination with a stationary door jamb and a movable door whose bottom is spaced above the floor, of a device for closing the opening between the door and the floor, said device comprising a pair of longitudinally extending U-shaped telescopic sheet metal members, one of which is secured to the bottom of the door, the other of which is movable longitudinally and vertically of said first mentioned member, spaced links pivotally connecting said members together, the web of said movable member being slotted to receive said links, a strip of yieldable material removably secured in said movable member between its opposed inner walls and projecting therebeyond, a spring connecting said members and urging said movable member to swing in an arc upwardly and longitudinally about the pivots of said links to project its end beyond said door and into the path of the door jamb, whereby said projecting portion may be engaged by the door jamb during the door closure to effect the closing of said opening.

In testimony whereof, we have hereunto signed our names in the presence of two subscribing witnesses.

JOHN G. WRIGHT.
HARRY F. BENNETT.
